UNITED STATES PATENT OFFICE.

HENRY K. STONER, OF LANCASTER, PENNSYLVANIA.

IMPROVEMENT IN HORSE-RAKES.

Specification forming part of Letters Patent No. 38,769, dated June 2, 1863.

To all whom it may concern:

Be it known that I, HENRY K. STONER, of Lancaster, in the county of Lancaster and State of Pennsylvania, have invented a new and Improved Device for Holding and Securing the Iron Teeth used on Horse-Rakes; and I do hereby declare that the following is a full, clear, and exact description thereof, reference being had to the accompanying drawings, making a part of this specification, in which—

Figure 1 is a perspective view of the device or tooth-head with a spiral spring attached thereto, the screw-bolt and burr G H detached. Fig. 2 shows the same with the tooth, &c., in place; also, the eye I of the tooth, through which the bolt enters to fasten the tooth on B and prevent its vertical action, confined in the notch f, resting on the beveled base c of the head A, shown one-third full size, clearly illustrating its construction and application.

Any number of [the tooth-heads are employed—one for each tooth—side by side on a rod, M, passing through the perforated ears D D. The teeth L are laid in the notch f on c, and bolted on the raised head B, so that each tooth may be raised independently on its head, or collectively, as the case may be. By confining the teeth in a notch the elasticity of the teeth perform their raking functions better than when allowed to vibrate or turn on the bolt G, instead of with the head on the rod M. The open notch f, bolt, and screw facilitate also the replacing of a broken tooth, and by attaching the spring F directly to the head

A or its projecting tooth-support c the necessity of loosening the spring will be avoided. In the case where keys are employed to hold the springs they must first be removed before the tooth can be replaced, which is always troublesome.

The device for holding the tooth firmly in its place on the bolt to prevent its vibration, confined as shown, the oscillating or vibrating tooth-heads, with the springs directly attached to them instead of being attached to keys, makes this a highly-desirable improvement on horse-rakes; and although I am aware that various kinds of tooth-heads and springs are employed, I am not aware of any that are substantially the same. And the advantages obtained by this simple device is believed to be as novel as it is useful in the construction and application of the teeth and springs to the same.

What I claim as my invention, and desire to secure by Letters Patent, is—

1. The construction and application of the tooth-head A, with its perforated ears D D raised, and notched flange B f for holding and securing the teeth, in the manner specified.

2. The supporting and projecting base c, in combination with the projecting flange, with its notch, for the additional purpose of attaching the springs, in the manner specified.

HENRY K. STONER.
